UNITED STATES PATENT OFFICE.

THOMAS G. HAWKES, OF CORNING, NEW YORK.

DESIGN FOR A GLASS VESSEL OR DISH.

SPECIFICATION forming part of Design No. 25,386, dated April 14, 1896.

Application filed March 2, 1896. Serial No. 581,585. Term of patent 14 years.

To all whom it may concern:

Be it known that I, THOMAS G. HAWKES, a citizen of the United States, and a resident of Corning, in the county of Steuben and State of New York, have invented and produced a new and original Design for a Glass Vessel or Dish, of which the following is a specification, reference being had to the accompanying drawings, forming part thereof, in which—

Figure I is a bottom view of a glass dish, showing my design. Fig. II is an axial section thereof.

The leading features of my design consist of a large double cross or asterisk figure covering the body of the dish, having radial pointed arms, a central rosette at the crossing of the arms forming the body of the figure, cross-hatching on the arms and double lines extending lengthwise of the arms, thus representing leaves having stems, checkered cutting at the inner ends of the arms, and foils between the

arms having rosettes, thus forming what I call the "Aberdeen" design.

A large central rosette on the body of a double cross or asterisk figure covering the body of the dish has radial pointed arms and produces foils between the arms. Cross-hatching appears on the arms and double lines extend lengthwise of the arms, thus representing leaves having stems. At the inner ends of the arms are checkered cuttings. Rosette figures appear in the foils located between the radial arms.

Having thus described my invention, the following is what I claim as new therein and desire to secure by Design Letters Patent:

The design for a glass vessel or dish, substantially as herein shown and described.

THOMAS G. HAWKES.
